VALVULAR FILLER SPOUT

Walter T. Etzel, Philadelphia, Pa.

Application October 2, 1931, Serial No. 566,465

25 Claims. (Cl. 226—127)

This invention relates to filler spouts for dispensing fluids, and in particular, to improvements in valvular filler spouts.

The type of valvular spout hereunder considered is especially applicable for dispensing volatile liquids as gasoline at filling stations and the like, where it is difficult, tedious, and oftentimes, particularly at night, impossible to accurately gauge the height of liquid column in a tank or container being filled.

Then too, since the maximum return on the investment often requires a minimum number of operators, and since business during the day and week comes more or less in "spurts", each operator is often so "pushed" that he must employ every second of his time, and in the "rush", very frequently, when told to "fill it up", runs the tank over. This latter condition not only antagonizes the driver of a recently polished car, and adds to the fire hazards, but also wastes the fluid being dispensed to the prejudice of either the gasoline, oil, or liquid dealer, or the car owner, himself.

The attendant or operator should have some form of dispensing mechanism that enables him to positively bring the level of fluid in a container to a desired height without the necessity of constant inspection and attention, and that will even enable him to take care of other duties while fluid or liquid is being dispensed, with the assurance that no loss, damage, or difficulty will occur in his absence.

Although there have been devised forms of filling nozzles or spouts for the above-mentioned purposes, to my knowledge, none of them have come into general usage. Some have such a needless complexity of parts that efficient and consistent sensitiveness of operation is impossible; some are so crude that satisfactory operation is impossible; others require such a lengthy snout that the space limitations set by the majority of automobile manufacturers in the location of the tap, bung, or filler hole are clearly violated; others make no provision for varying the depth to which the tank, vessel, or receptacle may be filled; still others require a constant motivation in order that the shut-off valve may operate at the proper instant, and, it has been an object of my invention to provide an improved form of valve that will overcome disadvantages of present devices.

Another object of my invention has been to devise a nozzle for dispensing liquids that is easy to manipulate and handle.

Another object of my invention has been the

provision of a nozzle valve that is positive yet sensitive in operation.

A further object of my invention has been to provide an efficient, effective, simple, and inexpensive form of valvular nozzle or filler spout.

These and many other objects of my invention will appear to those skilled in the art from the following description taken in conjunction with the drawing, in which:

Figure 1 is a vertical elevational view in section of an illustrative embodiment of my invention;

Fig. 2 is an enlarged view in perspective showing a detail; and

Fig. 3 is an end sectional view of another detail taken along line III—III of Figure 1.

In the drawing the numeral 10 is representative of the valvular nozzle or spout as a whole. The nozzle 10 includes an inlet chamber, pipe, or tube 11 in which a valve 16 is inclinedly disposed, an outlet or discharge chamber, pipe, or tube 12 having a float chamber 12a therein, and a mount and guard system 25—26—31 having an operating mechanism mounted thereon.

As shown, the inlet member 11 is divided into two compartments by an inclined partition member 14 that has a fluid passage or port 15 therein whose edges may be tapered to better form a valve seat. In order that the flow of fluid through the partition 14 may be limited or controlled, a suitable overhead or upwardly opening valve 16 has been provided. The valve 16 may be

of annular form having a cone-shaped or diverging bottom portion, an upper portion of hollow or sleeve construction, and a middle portion grooved for receiving a seat washer 18 of some suitable material such as fiber, leather, or soft metal. The upper portion of the valve 16 has a cup-like form to receive a spiral positioning spring 19 therein, and is slidably disposed within and sealed from fluid in the chamber 11 by an inspection cap 22 that is removably secured within upwardly projecting threaded portions 21 of the inlet member 11. The inspection plug 22 may be provided with an ordinary form of wrench-flat

in order that it may be tightly secured in locking position as well as readily removed thereafter. It will be noted that the spring 19 is protected from the fluid by the plunger-like fit between the cup-like valve sleeve and the inside of the cap 19.

The lower portion of the valve 16 has a stem 17 extending downwardly therefrom. As seen, the member 11 is provided with a downwardly inclined positioning extension through which the valve stem 17 extends. In order to provide a

fluid tight seal, I have inserted suitable packing 23 between the extension of the member 11 and the valve stem 17. The packing 23 is adjustably held in place by a slideable packing sleeve 23a; the latter in turn, is adjustably held in a given position by a threaded packing cap 23b.

The right-hand or open end of the inlet tube 11 is internally threaded to receive the ordinary form of filler tube or hose (not shown); but the other end of the inlet tube 11 and the upper end of the discharge tube 12 may be threaded to receive an elbow 31 for connecting them to form a unitary and continuous member. Although, for the purposes of inspection and repair, a threaded or removable elbow may be preferable, any form or fit may be employed. If desired, the discharge pipe 12 may be provided with a short length of flexible hose.

By devising two independently separate and parallel chambers or passages in the discharge spout 12, I have been able to not only eliminate any dead end space, and to materially lessen the length of the spout, but in addition, to accurately gauge the amount of gasoline or other fluid fed into the tank being filled and to carry out such gauging practice between wide limits or between a wide scale or range.

The inner or float chamber 12a is sealed from the inside wall of the discharge spout 12, in order that fluid can enter therein from the bottom only. A float 36, itself of cylindrical form and of floatable construction such as of thin metal, is disposed within the chamber 12a to gauge or indicate the liquid level of the tank being filled and thus to indirectly control the operation of the valve 16.

The outer wall of the discharge pipe 12 may be suitably calibrated for different size tanks and in addition, may be calibrated to different liquid levels, irrespective of actual liquid measure. To aid in this, a sliding ring 49 may be mounted on the outer circumference of the outlet spout 12 and adjustably set by the thumb screw 50 to register on the scale the liquid level or quantity desired. Of course, the ring 49 accomplishes its purpose by reason of the fact that it may be adapted to abut against and rest upon the edge of the filler hole and limit the depth or penetration of the lower end of the discharge pipe 12. In order that a position selected may be positively held, the thumb screw 50, and if desired, a series of set depressions 51 may be provided.

In order that the valve operating mechanism may be compactly, securely, and effectively mounted in a proper position, I have furnished a mount frame and guard system designated by the numerals 25, 26, and 31. The inlet member 11, and the outlet member 12 are each respectively provided with mounting lugs extending from the outer walls thereof and at their point of juncture may be provided with a common lug 25 projecting therefrom. This frame or guard system is mounted to extend downwardly and inwardly from the inlet member 11 and sideways and inwardly from the outlet member 12 adjacent the angular bend therebetween. Suitable side enclosing plates 27, one of which is shown, may be mounted over the mount and guard system in order to suitably protect the operating mechanism. In the drawing of Figure 1, the left-hand plate has been removed showing the mounting screw holes while only the right-hand plate is in place.

The operating mechanism or lever system includes resetting mechanism, trip mechanism,

lost-motion mechanism, balance mechanism, and float means. In the drawing of Fig. 1, the dotted lines represent the relationship of the various members when the operating mechanism has been moved by the float 36 into a valve-releasing or closing position; the full lines represent the relationship when the valve is set at an open position.

Since the spring 19 normally holds the valve 16 in a closed position, it follows that the operating mechanism must compress the spring during normal periods of fluid flow and must release it when the desired height of liquid in the container has been reached. In order to attain this result, a lever system has been devised which includes a valve operating or lever guide 24 having a practically straight portion upon which is formed a valve-stem seat (see Fig. 1), the end of which is bifurcated and pivotally secured by pivot means to the centrally extending lug 25.

The other substantially half or the extending portion of the guide lever 24 is upwardly concaved or curved to cooperate with the reset mechanism which includes a reset cam 28 rigidly secured on a pivot shaft 29 (see Fig. 2) which in turn, is pivotally supported between bifurcated ears 30 extending upwardly from the upper surface of the partition 31.

In order that the operator may partially rotate the cam 28 and raise the valve guide lever against the resiliency of the spring 19 into a valve opening position, the right end of the shaft 29 (from the attendant's normal position) extends through the right-hand cover 27 a distance sufficient to permit a knurled knob 32 (see Fig. 2) to be secured thereto.

As seen, the cam 28 has two oppositely projecting faces, the upper of which may be rounded to smoothly lift the curved portion of the guide lever 24, the lower end of which is pointed, in order that during the period when the cam is in a raised position the lower end will extend downwardly through a slot cut centrally through the longitudinal partition member 31 and cooperate with and reach into a complementary slot 35 cut in a catch lever 33. The catch lever 33 is pivotally secured within the upper portions of the bifurcations of a downwardly extending lever-mounting lug 34. The other, or the extending end portion of the catch lever 33 is adjustably connected to a "lost motion" link 40, which in turn, is adjustably connected to a balance lever 39.

As seen, the upper end of the connecting arm 40 is longitudinally slotted at 41 in order that it may be slidably pivoted in a "lost motion" manner to the catch lever 33. The elements 33, 40, and 39 may be pivotally connected together by cotter or any suitable form of pivot pins. The effective length of the slot 41 substantially represents the distance of slide of the connecting arm 40, and thus, represents the distance of rise of the balance lever 39 before the lower end of the slot 41 abuts the connecting pin of the catch lever 33 and pushes the end of such catch lever upwards about its pivot point to release the cam 28. The slot 41 may be lengthened or shortened or equipped with a variable slide, if desired, in order that any degree of lost motion between the travel of the slot 36 and the operation of the tripping mechanism may be attained.

The balance lever 39 is pivotally connected to the outer portions of the bifurcated mounting lug 34 and has an arm extending through a slot 75

in the float chamber 12a; this arm is suitably drilled out to receive a wire connector 38 suspended in pendulum-like fashion therefrom and supporting a float 36.

5 The other end of the balance lever 39 is provided with "quick-shift" balance portion 43 having a cylinder whose capacity may be varied by moving an end cap 45 (see Figs. 1 and 3) in and out of the open end thereof and which may be 10 locked in place by a cotter pin extending through complementary holes.

The balance-change medium may consist of a ball bearing 44, or some heavy liquid such as mercury. To accomplish an adjustment of the 15 effectiveness of the weight 44, the cap may be varied as above suggested. It will thus appear that the lever 39 may properly be termed a "balance" lever in that it is balanced at one end by the float 36 and at the other end by the 20 ball 44.

In order that the valve 16 may be snapped shut by the operator at any time, regardless of the amount of fluid in the tank being filled, a trip mechanism including a lever 46 is pivotally 25 mounted to extend through the frame member 26. The lever 46 has a downwardly extending dog 47 adapted to cooperate with the cylinder 43 of the "quick-shift" mechanism. The upper end of this dog portion 47 is normally held out of 30 abutment with the cylinder 43 and in a raised position by a spiral spring 48 secured between the end thereof and the partition member 31.

The operation of my invention will be briefly 35 described.

If the slide ring 49 is employed, it is set to give the desired depth of liquid in the tank or receptacle to be filled and the discharge nozzle 12 is placed in the filler hole.

Then, to set the valve 16 to an open from a 40 closed position, the knurled knob 32 on the end of the reset cam shaft 29 is turned or partially rotated in a forward or clockwise direction until the lower face portion of the cam 28 slides into a "set" or locked relation with the slot 35 of the 45 catch lever 33; this rotation causes the other end of the cam 28 to raise the guide lever 24 and the valve rod or stem 17 against the resiliency of the spring 19. Thus, the spring 19, by reason of its compressive force, holds the cam 28 and the 50 catch lever 33 in cooperating relationship until released by other mechanism. Now, the filler nozzle 10 will permit a flow of fluid in the direction indicated by the arrows through the inlet pipe 11, past the valve 16 and out through the 55 discharge pipe 12.

As the flow of liquid is initiated and fluid rushes into the tank or container, the float 36 will slowly rise until the lower end of the slot 41 in the connecting or "lost motion" arm 40 contacts with 60 the pivot pin of the catch lever 33, after which the extending end of the catch lever 33 is raised and the cam 28 is snapped out of complementary relationship with respect to the slot therein by the force of the compression spring 19. Simultaneously, of course, the valve 16 is snapped shut.

Since the variable balance weight or ball 44, shifts from one position to another when the balance lever 39 is at one end raised or lowered a short distance, the action of the mechanism is quickened, since the momentum produced by sudden shifting of the weight, tends to speed up and aid the balancing action of the gravity on the lever system.

Although I have shown a particular embodiment of my invention for the purpose of illus-

tration, yet many modifications, substitutions, omissions, and the like may be made without departing from the spirit and scope of my invention.

What I claim as new and desire to secure by Letters Patent is:

1. In a filler spout, the combination of a resiliently positioned valvular means disposed therein for limiting and controlling fluid flow therethrough, said valvular means having an extending stem, an operating lever pivotally mounted on said spout and having a seat portion cooperating with the extending end of the stem of said valvular means, a reset cam mounted on the spout and having a face cooperating with 10 said operating lever for raising it to a valve-opening position, and means cooperating with said cam for holding it in a valve-opening position.

2. The combination with a filler spout, of a

valve positioned therein for controlling fluid flow 20 therethrough, said valve having a stem extending outwardly through said spout, an operating lever pivotally mounted on said spout and having a seat portion adjacent its pivot point cooperating with the end of said extending valve stem, said operating lever having an upwardly concaved portion near the extending end thereof, a cam having a face cooperating with said concave portion for raising said lever to a valve opening position, a catch lever for cooperating with an opposite face of said cam for holding it in a raised position, and means for tripping said catch lever and releasing said cam, and means for then moving said valve to a closed position.

3. In a filler spout having inlet and outlet 35 chambers, the combination of a resiliently-pressed valvular means operatively disposed within said inlet chamber for controlling fluid flow therethrough, said valve having an extending stem for cooperating with a valve-opening lever; an operating mechanism, said mechanism including a catch lever, a balance lever connected to said catch lever, an operating and valve-opening lever cooperating with said valve stem, and a cam 40 cooperating with said operating lever and said catch lever.

4. In a filler spout, the combination of a resiliently positioned valve operative therewithin, said valve having a stem extending outwardly through 45 said spout, an operating lever positioned on said spout, said operating lever having a portion contacting with said valve stem, a reset cam having a smoothly curved cam face cooperating with said operating lever for raising said lever and opening said valve against the resiliency thereof, said cam having a relatively abrupt face at the other end thereof, a catch means slotted for receiving the abrupt face of said cam and holding it in a moved position, a float movably supported in said nozzle and connected to said catch means for releasing said valve when fluid in a container being filled has reached a predetermined level.

5. In a filler spout having inlet and discharge 60 chambers, the combination of a spring-pressed valve operatively disposed within the inlet chamber for controlling fluid flow therethrough, a float chamber disposed within and sealed from said discharge chamber, a float operatively disposed within said float chamber, operating means for raising said valve to an open position against the resiliency of the spring, said operating means being connected to said float for actuation thereby, said operating means including a balance system 65 having a catch-release lever assisted by resiliency 70

75

of the spring of said valve for closing said valve from an open position.

6. In a filler spout having inlet and discharge chambers, the combination of a spring-pressed valve operatively disposed within the inlet chamber of said spout, said valve having a stem extending therefrom, an operating lever pivotally mounted on said spout and having a face adjacent its pivot point for seating the stem of said valve, said operating lever having an upwardly curved outline adjacent said seating face toward an end thereof, a pivoted catch lever, a reset cam having two opposite faces, one face of which being smoothly curved for raising said operating lever to a valve-opening position, the opposite face of said cam being sharp for cooperating with said pivoted catch lever and holding said cam in a raised position, a "lost motion" link, a pivotally positioned balance lever connected to said catch lever by said "lost motion" link, a float disposed within said discharge chamber and connected to said balance lever, so that when fluid in a container being filled has reached a given height that said float will move said balance lever, and subsequently, move said catch lever after lost motion of said "lost motion" means is taken up.

7. In a filler spout having a body member and a discharge member, the combination of a spring-pressed valve operatively positioned in said body member, a lever for unseating said valve, means for holding said lever in a valve unseating position, a float in said discharge member, a slotted-pivot means connected between said lever holding means and said float for permitting said float to rise without affecting said lever-holding means, and means cooperating with said slotted pivot means for instantaneously releasing said lever-holding means when said float reaches a predetermined level.

40 8. In a filler spout having inlet and outlet chambers, the combination of a valve operatively disposed in one of said chambers, a lever cooperating with said valve for holding it in an open position, a cam cooperating with said lever for holding it in a valve-opening position, a float disposed within the other chamber, mechanism connected to said float and cooperating with said cam for releasing said lever and permitting said valve to close, said mechanism including lost-motion means permitting limited travel of said float without operating said cam, and including means for instantaneously releasing said cam when said float has traveled a predetermined distance.

55 9. In a filler spout having inlet and outlet chambers, the combination of a valve mounted in the inlet chamber for limiting fluid flow into said discharge chamber, a lever for moving said valve to an open and unseated position, a cam for locking said lever in a valve unseating position, a catch member cooperating with said cam for holding it in said locking position, a "lost motion" link pivotally connected to said catch member, a balance lever connected to said "lost motion" link, a float disposed in said discharge chamber and connected to one end of said balance lever, and means disposed within the other end of said balance lever for instantaneously releasing said cam when said float has reached a predetermined level.

70 10. In a filler spout, the combination of a valvular means disposed therein for controlling fluid flow therethrough, said valvular means having an extending stem, an operating lever at one end pivotally mounted on the spout and cooperating

with the end of said extending stem, a cam having oppositely projecting faces and being pivotally mounted on the spout, one of the faces of said cam being curved to cooperate with an extending end portion of said operating lever for raising it to a valve-opening position, and means cooperating with the opposite face of said cam for locking said cam in position.

5 11. In a filler spout, the combination of a valvular means disposed therein for controlling fluid flow therethrough, said valvular means having a stem extending therefrom, an operating lever at one end pivotally mounted on the spout and having a portion adjacent said end for seating the end of said valve stem, means mounted on the spout and abutting with said lever for raising it to a valve-opening position, and means for holding said last-mentioned means in a valve-opening position.

10 12. In a filler spout, the combination of a valvular means disposed therein for controlling fluid flow therethrough, a yieldable means for holding said valve in a closed position, a stem extending from said valve, an operating lever pivotally mounted on the spout and having a portion for seating said stem, and a cam for raising an extending end of said operating lever to a valve-opening position, and means for holding said cam in a raised position.

15 13. In a filler spout, the combination of valvular means disposed therein for controlling fluid flow therethrough, said valvular means having an extending stem, an operating means pivotally mounted on the spout and having a portion adapted to cooperate with said stem for raising said valvular means to an open position, a cam for holding said operating means in a valve-opening position, said cam having at least two faces one of which cooperates with said operating lever for holding it in a valve-opening position, and 20 a catch lever cooperating with the other face of said cam for holding said cam in a raised position.

25 14. In a filler spout, the combination of valvular means disposed therein for controlling fluid flow therethrough, said valvular means having an extending stem, an operating lever pivotally mounted on the spout and having a portion adapted to cooperate with said stem for raising said valvular means to an open position, a cam for holding said operating means in a valve-opening position, said cam having at least two faces one of which cooperates with said operating lever for holding it in a valve opening position, and a catch lever cooperating with the other face of said cam for holding said cam in a raised position, 30 said catch means being pivotally mounted on the filler spout and having a balance arm for releasing said cam.

35 15. In a filler spout, the combination of valvular means disposed therein for controlling fluid flow therethrough, said valvular means having a stem extending therefrom, resilient means for holding said valvular means in a closed position, an operating lever pivotally mounted on said spout and having a seat portion adapted to cooperate with the extending end of said valve stem, a cam having a face adapted to cooperate with said operating lever for raising it to a valve-opening position, and means cooperating with said cam for holding it in a valve-opening position 40 against the resiliency of said resilient means, and means for tripping said last mentioned means, so that said cam may be released and that said valvular means may be closed.

45 16. In a filler spout, the combination of a re-

- silently-positioned valvular means disposed therein for controlling fluid flow therethrough, said valvular means having an extending stem, an operating lever pivotally mounted on the spout 5 and having a portion adapted to cooperate with said extending stem, a cam having a face adapted to cooperate with a portion of said operating lever for raising it about its pivotal point to a valve-opening position, catch means for holding 10 said cam in a valve-opening position, said catch means being pivotally mounted and balanced on the spout, and means for upsetting the balance of said catch means and releasing the valvular means.
- 15 17. In a filler spout, the combination of a resiliently-positioned valvular means disposed therein for controlling fluid flow therethrough, said valvular means having an extending stem, a pivotally mounted operating lever, said lever having a portion adapted to cooperate with said extending stem, a cam having a face adapted to cooperate with said operating lever for raising it to a valve-opening position, a catch lever adapted to cooperate with another 20 face of said cam for holding it in a valve-opening position, said catch lever being pivotally mounted, and a lost-motion-release-means connected to an end of said catch lever.
18. In a filler spout, the combination of resiliently-positioned valvular means disposed therein for controlling fluid flow therethrough, said valvular means having an extending stem, an operating lever pivotally mounted on said spout and having a portion adapted to cooperate with said 25 extending stem, and means adapted to abut with and raise said operating lever to a valve-opening position, and means adapted to abut with said raising means for holding it in a valve-opening position, a manual-trip mechanism, said holding means including means sensitive to the level of fluid in a container being filled for automatically releasing said valve-holding means.
19. In a filler spout, the combination of resiliently-positioned valvular means disposed therein for controlling fluid flow therethrough, said valvular means having an extending stem, an operating lever pivotally mounted on the spout and having a portion adapted to cooperate with said stem, and means for moving said operating means to a valve-opening position, and a lever system including at least two levers connected together for holding said last-mentioned means in a valve-opening position and for releasing said means when a container has been filled.
20. In a filler spout, the combination of a resiliently positioned valvular means disposed therein for controlling fluid flow therethrough, said valvular means having an extending stem, an operating lever pivotally mounted on said spout and having a portion adapted to abut said stem, a cam having a face adapted to abut said operating lever for raising it to a valve-opening position, and a balance lever system adapted to cooperate with said cam for holding it in a valve-opening position and for releasing it from such position, said balance lever system including an automatic shift weight for increasing the sensitivity of action thereof.
21. The combination in a filler spout, of a valve positioned therein for controlling fluid flow there-
- through, said valve having a stem extending outwardly through said spout, an operating lever pivotally mounted on said spout and having a seat portion adjacent its pivot point cooperating with the end of said extending valve stem, said operating lever having an upwardly curved portion near the extending end thereof, a cam having a face cooperating with said curved portion for moving said lever to a valve-opening position, a catch means cooperating with an opposite face of 10 said cam for holding it in a moved position, and means for tripping said catch means and releasing said cam.
22. In a filler spout having suitable inlet and discharge chambers, the combination of a valve mounted within the inlet chamber for limiting fluid flow into said discharge chamber, a lever for moving said valve to an open and unseated position, a cam for locking said lever in a valve-unseating position, a catch member cooperating 15 with said cam for holding it in a locking position, a "lost motion" link pivotally connected to said catch member, a balance means connected to said "lost motion" link, a float operatively disposed in said discharge chamber and connected to said 20 balance means, and said balance means including means for instantaneously releasing said cam from said catch member when said float has reached a predetermined level.
23. In a filler spout, the combination of a valve disposed therein for limiting and controlling fluid flow therethrough, said valve having an extending stem, an operating lever pivotally mounted on the spout and having a portion cooperating with said valve means, a reset means for raising said 25 operating lever about its pivot point and opening said valve means, and a plurality of pivotally inter-connected levers pivotally mounted on said spout, at least one of said levers cooperating with said reset means for releasing said reset means 30 when the normal relationship of said levers is changed.
24. In a filler spout, the combination of a resiliently positioned valvular means disposed therein for limiting and controlling fluid flow therethrough, said valvular means having an extending stem, an operating lever pivoted to the spout and having a portion cooperating with said valve stem for moving said valve to an open position, a pair of levers pivoted to the spout, at least one 35 of said levers being a balance lever, one of said pair of levers having means for releasing said operating lever from a valve-opening position, the other lever of said pair having a fluid-level-sensitive means for operating the first-mentioned 40 lever of said pair.
25. In a filler spout, the combination of a resiliently positioned valve means operatively disposed therein for controlling fluid flow therethrough, an operating member for moving said 45 valve means to an open position, and a balance lever pivoted to the spout, and a cam operatively associating said balance lever with said operating member, said balance lever having a hollow chamber, and a ball operatively disposed in said chamber for accentuating an off-balancing of said balance lever, and fluid-level-sensitive means for upsetting the balance of said balance lever and permitting said valve to move to a closed position.
